Attorney.

UNITED STATES PATENT OFFICE.

GEORGE M. BRILL, OF PHILADELPHIA, PENNSYLVANIA.

DESIGN FOR A TRUCK SIDE FRAME.

SPECIFICATION forming part of Design No. 26,383, dated December 8, 1896.

Application filed April 6, 1894. Serial No. 506,634. Term of patent 14 years.

To all whom it may concern:

Be it known that I, **GEORGE MARTIN BRILL**, a citizen of the United States, residing at Philadelphia, in the county of Philadelphia and State of Pennsylvania, have invented and produced a new and original Design for a Truck Side Frame; and I do hereby declare the following to be a full, clear, and exact description of the same, such as will enable others skilled in the art to which it appertains to make and use the invention.

My invention relates to a truck side frame; and its essential feature resides in the design as shown.

5 In the drawings forming part of this specification, Figure 1 is a side elevation, and Fig. 2 an end elevation, of the truck side frame.

2 an end elevation, of the truck side frame. My truck side frame comprises the longitudinal side bar 1 with inverted-U-shaped yokes 2 extending above the bars 1, the said bar extending beyond the yokes, as at 3, the yokes having the depending lips 4. The extensions 3 of the bar 1 from the yokes outward are bifurcated, as at 5 6, the extreme 5 end of which is joined by the bed-plate 7, which has two horizontal extensions or ears 8. The side bar is rectangular in cross-section. Lying above and parallel with the side bar is a flat rectangular bar 9, from the proximate

ends of which depend inverted-U-shaped yokes 10, flat externally, and above the bed-plates 7 lie inverted-U-shaped yokes 11, having outwardly-extending flat ears 12, lying on the ears 8. About the yokes 2 and extending upwardly between the side bars 1 3 and bar 9 are circular spiral springs 13, and from the bar 9 through the springs and to and through the side bar extend circular rods 14, between which extends a flat bar 15. Extending between the ends 3 of the bar 1 and bar 9 and embraced by the yokes 10 and 11 are longitudinally and vertically disposed elliptical springs 16, the inner ends of which extend over the ends 3 of the bar 1 and toward the springs 13. 45

All of the parts are secured together and form a single unitary structure, and the entire frame is rectangular in its exterior aspect.

I claim—

The design for a truck side frame, substantially as herein shown and described. 50

Signed at Philadelphia, in the county of Philadelphia and State of Pennsylvania, this 3d day of April, 1894.
